UNITED STATES PATENT OFFICE.

ELWOOD E. SEACRIST, OF MEADVILLE, PENNSYLVANIA.

APPARATUS FOR RECLAIMING METALS FROM WASTE.

1,253,539.

Specification of Letters Patent. Patented Jan. 15, 1918.

Application filed August 1, 1917. Serial No. 183,933.

To all whom it may concern:

Be it known that I, ELWOOD E. SEACRIST, a citizen of the United States, residing at Meadville, in the county of Crawford and 5 State of Pennsylvania, have invented certain new and useful Improvements in Apparatus for Reclaiming Metals from Waste, of which the following is a specification.

This invention relates to apparatus for 10 reclaiming metals from waste and has for its object the provision of means whereby copper, brass or other metals may be reclaimed from the slag, ladle skimmings, floor waste, etc., of bronze mills, brass foundries and the 15 like.

It is well known that in metal mills and foundries a considerable quantity of valuable metal is present and usually thrown away in the slag, ladle skimmings and floor 20 accumulations. The importance of this waste was realized some time ago and as a consequence various methods and apparatus have been devised for the reclamation of such metal. The present practice is to gran- 25 ulate the slag, etc., wash it with a stream of water to remove the sand and other debris and then dry the metallic residue as a pre- liminary step to returning it to the melting furnace. These various operations consume 30 considerable time and require the services of several men with a consequent too great item of expense.

It is with these facts in view that the 35 present invention has been designed which contemplates the provision of means whereby the waste, after being granulated, is subjected to a winnowing action to remove the useless fragments and particles and leave the particles of metal in a dry state ready 40 for remelting, the operation requiring the attention of only one operator and being continuous in its action.

A further object of the invention is the 45 provision of a device of this character which will be simple in construction, inexpensive in installation and maintenance, durable in service, and a general improvement of the art.

With these objects in view the invention 50 consists in the novel features of construction and arrangement to be hereinafter more fully described and claimed, and illustrated in the accompanying drawings in which:

Figure 1 is a longitudinal sectional view 55 through the device, and

Fig. 2 is a cross sectional view.

Referring more particularly to the drawings, the numeral 1 designates a downwardly inclined barrel provided adjacent its upper and lower ends with circumferential flanges 60 2 and 3 revolvably mounted in bearing members 4 and 5 carried by supporting standards 6 and 7. An exhaust pipe 8 is secured upon the outer side of the bearing member 4 and extends coaxially with the barrel for a short 65 distance, as shown at 9, and then extends upward at a greater inclination, as shown at 10, terminating in a horizontal portion 11. A baffle plate 12 is disposed within the ex- 70 haust pipe 8 at the junction of the in- clined portion 10 with the horizontal por- 75 tion 11. The lower side of the inclined portion 9 of the exhaust pipe is provided with an opening 13 at the forward edge of which is secured a deflecting plate 14 inclined up- 70 wardly to the inner periphery of the bearing member 4. A chute 15 is secured to the standard 6 below the opening 13, as shown.

A feed hopper 16 is mounted on the in- 80 clined portion 10 of the exhaust pipe and has its end portion 17 extending through the inclined portions 10 and 9 of the pipe 8 and into the barrel 1.

A fan blower 18 is mounted near the lower 85 end of the barrel and has its discharge end 19 extending a short distance into and spaced from the side of the barrel. For controlling the blast a gate valve 20 is pro- 90 vided.

The barrel 1 may be rotated in desired 90 manner though I show it as provided with a worm wheel 21 meshing with a worm 22 carried by a shaft 23 journaled in bearings on a support 24. The means for rotating the barrel and blower is immaterial, though I 95 have shown a motor 25 provided with a pulley 26 over which is trained a belt 27 further trained about a pulley 28 secured on a counter shaft 29 mounted in bearings on a sup- 100 port 30. A pulley 31 is also secured on the shaft 29 and has trained thereon a belt 32 further trained about a pulley 33 on the blower shaft. A third pulley 34 is secured on the shaft 29 and has trained thereon a belt 35 further trained about a pulley 36 105 on the worm shaft 23.

For an important purpose which will pres- 110 ently become apparent, I provide the interior of the barrel 1 with a plurality of longitudinally extending strips 37 which may be conveniently in the form of angle irons, as shown, and which are spaced equally apart.

The operation of the device is as follows: The slag, etc., containing the metal to be reclaimed, after being reduced to a granulated state, is placed in the hopper 16 from which it will pass through the portion 17 into the barrel 1. By virtue of the pulleys and belt-
 5 ing described, the barrel is constantly rotating and the blower is delivering a blast through the barrel. As the granulated material enters the barrel, it will be caught by the strips 37 and carried upwardly there-
 10 by to a certain distance, whereupon by force of gravity it will fall from the strips back to the lower side of the barrel. While the material is thus falling, the blast from the blower will blow the lighter particles into the exhaust pipe 8, leaving the heavier particles—the granules of metal—in the barrel. On account of the vibration these metallic
 15 particles will gradually work down to the lower end of the barrel from which they will drop into a suitable receptacle 38 placed thereunder. From actual practice it has been found that a speed of fifteen revolutions of
 20 the barrel per minute is most satisfactory. Using three strips in the barrel, this speed will cause the material to fall in a sheet or curtain within the barrel forty five times in a minute, insuring that every bit of the
 25 granulated material will be exposed thoroughly to the winnowing action of the blast. The gate valve 20 is of course adjusted so that the strength of the blast will not be great enough to blow heavy particles of
 30 metal into the exhaust pipe.

To this point, only the heavier metallic pieces will have been reclaimed. As the lighter particles of metal are blown back up through the barrel with the particles of
 35 waste, the waste which is the lightest, will pass up through the uncurved portions 9 and 10 of the exhaust pipe and out through the horizontal portion 11 in the form of dust. The light metallic particles are still heavier
 40 than the waste and will strike against the plate 12 and slide back down the inclined portion 10 and out through the opening 13 into the chute 15 from which they will drop into a suitable receptacle 39.

45 50 After the heavier particles of metal have been thus collected at the lower end of the barrel and the light or flaky particles at the lower end of the exhaust pipe, further

reclamation may be made, if desired, by reducing the force of the blast and running the exhaust dust through the apparatus.

55 From the foregoing description and a study of the drawings it will be apparent that I have thus provided a simple and efficient device whereby the particles of metal 60 may be removed from slag, ladle skimmings and other wastes, in a dry state and in proper condition for remelting without further preliminary treatment.

65 It will be readily understood that I reserve the right to make such changes in the form, construction and arrangement of parts as will not depart from the spirit of the invention or the scope of the subjoined claims.

I claim:

70 1. A device of the character described, comprising a rotary inclined barrel provided with projections on its inner periphery, an exhaust pipe surrounding and communicating with the upper end of said barrel and inclined upwardly at a greater angle than said barrel, a feed hopper extending through said exhaust pipe and into the upper end of said barrel, said exhaust pipe being provided in its lower side adjacent said barrel with 75 an opening, a baffle plate at the upper end of the bottom of said exhaust pipe, and an air blast conducting pipe extending into the lower end of said barrel and spaced from the periphery thereof.

80 85 2. A device of the character described comprising an inclined rotary barrel, a blast conducting pipe extending axially into the lower end thereof, a stationary exhaust pipe inclined in the same direction as and at a 90 greater angle than said barrel and having its lower end surrounding and communicating with the upper end of said barrel, a feed hopper extending through the top of said exhaust pipe and into said barrel, the lower 95 end of the bottom wall of said exhaust pipe being provided with an opening adjacent the end of said barrel, a vertical baffle plate secured upon the highest portion of the bottom wall of said inclined exhaust pipe, and a 100 horizontal discharge pipe of the same diameter as and communicating with the upper end of said exhaust pipe.

95 In testimony whereof I hereto affix my signature:

ELWOOD E. SEACRIST.
